FLUSH HANDLE LATCH

Robert P. Kuszmaul, Indianapolis, Ind.

Application December 13, 1934, Serial No. 757,339

12 Claims. (Cl. 70—146)

This invention relates to latches and particularly to a latch which may be operated by a handle swinging in a horizontally described arc. A primary object of the invention is to provide a latch operating mechanism of a very simple and inexpensively formed construction with which an operating handle may be employed to be sunk within the door or movable member to which the latch is applied whereby the handle will not project beyond the outer surface of that door or member. A further important object of the invention is to provide along with the latch mechanism simple means for locking or rendering the latch operating means ineffective from one side of the door by simple reverse movement of an operating handle and also to provide a key operated locking structure for controlling the locking of the mechanism from the other side of the door.

20 A still further important object of the invention is to provide in the latch mechanism those features which will permit the door to be closed even though the inner or outer locking devices have been previously set to lock the mechanism, 25 and further to include that feature wherein the latching mechanism is returned to a normal unlocked position in respect to the inner locking feature.

Other objects and advantages of the invention will become apparent to those versed in the art in the following description of the invention as illustrated by the accompanying drawings, in which

Fig. 1 is a fragmentary side elevation of a door to which my invention is applied;

35 Fig. 2, an inside elevation of the latch mechanism assembly;

Fig. 3, a detail in vertical transverse section showing the key lock control;

40 Fig. 4, a vertical transverse section on the line 4—4 in Fig. 2;

Fig. 5, a horizontal transverse section through a door indicating the relative positions of the latch mechanism and control, and

45 Fig. 6, a similar transverse section but indicating a latch control with the latch mechanism in reversed position.

Like characters of reference indicate like parts throughout the several views in the drawings.

50 For convenience I employ a mounting plate 10 which may be a separate unit or may be an integral part of the door 11. I have herein shown the plate 10 to be a separate element and when so employed, the latch mechanism may be assembled thereon as a unit before applying the mechanism to the door. This plate 10 is formed to have one end 12 bent therearound to extend from the plate at right angles thereto and a hole is cut through this extension 12 to slidably 60 receive therethrough the latch bolt 13 which

extends from the plate end 12 along the inner face of the plate in sliding relation thereover to be secured and supported by the plate so as to permit longitudinal travel. In the form herein shown, the latch bolt 13 is provided with a longitudinally disposed slot 14 through which a member 15 passes to be rigidly held by the plate 10, the member 15 being here shown as a screw. The member 15 is provided with an outer head or retaining member here shown as a washer 16 so that the latch bolt 13 is constrained to longitudinal travel within the limits of the slot 14, the outer end of the latch bolt being supported by the plate end 12 through which it passes.

A rocker bar 17 is carried by the plate 10 to hang normally in a vertical position as indicated in Fig. 2. This bar 17 is provided with a slot 18 extending along the vertical center line of the bar and a supporting member 19 rigidly held by the plate 10 extends through the slot 18 and has a head on the outer end so as to hold the bar 17 in slidable contact with the plate 10. In the form herein shown, this member 19 is a screw and the head is formed by a washer 20 under the head of the screw and over the bar 17. The upper end of the bar 17 is turned outwardly from the plate 10 to have a horizontally extending arm 21 formed thereby, Figs. 2 and 3, and the outermost end of this arm 21 is preferably turned downwardly to form a lip 22. A spring 23 has one end fixed to the plate 10 and extends around from that fixed connection over the upper end of the bar 17 to compressibly engage by its free end against the top side of the arm 21, thereby tending to push the bar 17 downwardly along the member 19 until the upper end of the slot 18 contacts therewith.

The rocker bar 17 extends downwardly in sliding contact with the plate 10 to immediately above the latch bolt 13 and is then carried outwardly from the plate 10 and thence downwardly over the latch bolt 13 in close proximity thereto, but with sufficient clearance to prevent interference with the horizontal movement of the latch bolt. The bar 17 is carried downwardly a distance below the latch bolt 13 in the same plane and is then bent rearwardly and then downwardly to have its lower end in sliding contact with the plate 10.

55 In the lower end of the rocker bar 17 is provided a vertically disposed slot 24 through which extends a post 25 here shown as in the form of a screw, rigidly supported by the plate 10, to have a retaining head or member 26, a washer in the form shown, so that the lower end of the bar 17 is retained in that sliding contact with the plate 10. The location of the post 25 is such that it will be at the upper end of the slot 24 when the bar 17 is in its lowermost position in respect to the upper post 19.

The lower end of the bar 17 is provided with an extending portion 27 which extends toward the plate end 12. This extending portion carries a slot 28 which opens into the slot 24 in its upper end and is so formed as to permit the rocker bar 17 to swing by its lower end rearwardly from the plate end 12 with the center of oscillation being at the center of the post 19 and the slot 28 providing an opening for the lower post 25 as the end swings therewith. In this connection, the slots 18 and 28 are so formed and the posts 19 and 25 are so located that the rocker bar 17 may swing as indicated without causing the rocker bar 17 to bind on the latch bolt 13.

The latch bolt 13 is provided with a horizontally out-turned lug 29 to be immediately back of and normally in contact with the back vertical edge of the rocker bar 17. A torsional spring 30 is fixed by one end to the plate 10 and is carried from that fixed point upwardly and toward the rear end of the latch bolt 13 and thence extends upwardly and rearwardly to leave a hump 31 in compressive contact with that rear end of the latch bolt 13. This spring 30 thus normally urges the latch bolt 13 to carry the lug 29 into engagement with the rocker bar 17. I provide an arm 32 to extend from the rocker bar 17 at some point below the post 19 as a means of rocking the bar 17 back against the lug 29 to retract the latch bolt 13. This arm 32 is here shown as being located on the forward edge of the rocker bar 17 to extend outwardly from that portion immediately below the latch bolt 13 although the exact location is immaterial and is dependent upon the desired location of the outer latch operating handle 33.

Referring to Fig. 5, the door 11 is provided with a recess or countersink 34 within which the handle 33 may lie normally so that its outer surface will not project beyond the outer face of the door. The forward end of the metal defining the countersink 34 is cut through to permit the handle to extend through that metal to within the door to have the handle rockably mounted on a vertically disposed pin 35 supported by a bracket 36 preferably secured to the inner side of the door. From the pin 35 an arm 37 extends integrally from the handle against the plate end 12, and from the contact therewith the arm extends backwardly to have its end adjacent the arm 32 carried by the rocker bar 17 with a slight clearance therebetween. In order to maintain the handle 33 normally within the countersink 34, I provide a torsional spring 38 which is wrapped about the pin 35 to have one arm turned around into engagement with the handle arm 37 and the other end of the spring turned to have a foot 39 bearing against the inside of the door or the bracket 36. It is thus to be seen that regardless of the position of the rocker bar 17, the spring 38 normally retains the handle 33 in the counter-sink 34 by having the arm 37 in abutment with the plate end 12. In the mechanism thus far described, the latch bolt 13 may be retracted from the outside of the door by pulling the handle 33 horizontally out of the recess 34 to cause the handle arm 37 to push against the rocker bar 70 arm 32 and thus in turn rock the bar 17 against the lug 29 to carry the latch bolt 13 inwardly over the plate 10 against the spring 38 which tends to resist that travel. Release of the handle 33 will permit the spring 38 to return the handle 75 to its normal position and to permit the spring

30 to return the latch bolt 13 to its normal extended position.

Particular attention is directed to the fact that the portion of the handle 33 which travels through the opening in the metal 40 forming the exterior of the door 11 is so shaped that regardless of the position in which the handle 33 may be carried, there is no opening left between the handle and that metal through which any wire or other instrument may be inserted to operate the latching mechanism within the door. This feature is obtained by the particular formation of the handle member as will now be described.

The handle 33 is formed with a heel 42 which is that part that travels through the opening in the metal 40. The vertical face 43 of this heel portion 42 is formed to have a curvature, the center of which is the center of the pin 35. The opposite face 44 of this heel 42 is likewise formed to have a curvature, the center of which is the center of the pin 35. The radii of the curvatures of these two faces 43 and 44 are made to be such that the faces are in very close proximity with the vertical edges of the opening through the metal 40 so as to leave substantially no clearance. The heel 42 thus formed extends inwardly first and then outwardly to around the pin 35 so as to provide the necessary clearance between the face 43 and that portion which surrounds the pin 35.

In order to lock the latch bolt 13 in the latched position, I provide a locking mechanism which is herein shown in the form of a cylinder lock 45, Fig. 3. This cylinder 45 is of the usual and well known mechanism which may be pushed inwardly within a sleeve 46 to a locked position and then be released by inserting a key into the cylinder. I mount the sleeve 46 in the present form as shown to be carried by the door 11 to extend inwardly from the outer side to have its inner end terminate adjacent the outwardly turned end of the arm 21. The inner end of the cylinder 45 is provided with a tapered member 47 which is pushed under the downturned lip 22 of the arm 21 as indicated by the dash lines, Fig. 3, when the cylinder 45 is pushed inwardly to its locked position. In this travel of the member 47, the rocker bar 17 is lifted as the inner end of the member 47 exerts a wedge-like action under the lip 22. When the rocker bar 17 is thus lifted to travel along the posts 19 and 25, the slot 28 is carried above the post 25 so that the post is then in the lower portion of the vertically disposed slot 24 and no rocking of the bar 17 may then be had. Also as the bar 17 is lifted, the leg 32 is carried upwardly out of the path of the inner end of the handle arm 37 so that even though the handle 33 may be pulled outwardly, that inner end of the arm 37 strikes nothing and consequently such movement of the handle 33 is ineffective as to causing any movement of the latch bolt 13 or any other parts connected therewith. The spring 30 of course retains the latch bolt 13 in the latched position and the spring 38 returns the handle 33 when released. Upon inserting the required key into the cylinder 45, the locking pin is released from engagement with the sleeve 46 and the return spring 48 carries the cylinder outwardly to permit the spring 23 to return the rocker bar 17 to its lower position as the member 47 recedes from under the lip 22 so as to restore the bar 17 to the position whereby it may be rocked by outward movement of the handle 33.

It is necessary of course to provide some means

for controlling the latch bolt 13 from the inside of the door. For this purpose I mount a stub shaft 49 on the plate 10 to have its axis horizontally disposed, and in the form herein shown 5 to be above the latch bolt 13. I mount the ordinary operating handle 50 on the outer end of this shaft 49, here shown as by telescoping the handle over the end of the shaft 49 and inserting a pin 51 through both members and then placing 10 a collar 52 to be urged outwardly to conceal that pin by a spring 53. The inner end of the shaft extends sufficiently through the plate 10 to carry a gear sector 54 thereon in fixed relation thereto. Inward shifting of the shaft 49 is prevented by 15 means of a horseshoe washer 55 which is forced down over the shaft across an annular groove therein as indicated in Fig. 2. The toothed periphery of the sector 54 is turned toward the latch bolt 13 and a slide 56 is provided with a 20 rack 57 to be engaged by the teeth of the sector while the opposite edge of the slide bears with 25 sliding contact against the longitudinal edge of the latch bolt 13.

The slide 56 is constrained to horizontal longitudinal travel by means of two spaced apart 25 posts 58 and 59 passing through the slide 56, the posts 58 and 59 being rigidly carried by the plate 10 and having heads or washers on their outer ends 30 to maintain the slide in sliding contact with the inner face of the plate 10.

The end of the slide 56 which is directed toward the rocker bar 17 is provided with a foot 61, the outer face of which is sloped downwardly and 35 outwardly toward that bar to provide a cam or wedge-like member. As the slide 56 may be carried toward the bar 17, the lower outer point of the foot 61 enters under the shoulder of the bar 17 immediately above the latch bolt 13, that 40 shoulder being formed by the off-set portion of the bar 17 which is carried around and down over the outer side of the latch bolt 13. Continued travel of the slide 56 will thus cause the foot 61 to lift the rocker bar 17 vertically to 45 bring the bar into that upper position wherein the lower end of the slot 24 engages about the post 25 so as to prevent any fore and aft rocking of the bar 17, thus preventing any movement of the latch bolt 13 from the outside of the door 11 by movement of the handle 33. This position of 50 the slide 56 is maintained by the spring 30 which has its upper end carried upwardly from the hump 31 and bent around to form an upper slide contacting foot 62 which yieldingly bears against 55 the edge or side of the slide 56. That portion of the under side of the slide 56 which is in the path of the spring foot 62 is formed to have an initial horizontally disposed surface 63 spaced upwardly in the form herein shown from the 60 under side of the slide 56 so that when the slide 56 is in its normal position, the lower point of the foot 61 is just in contact with the bar 17 and the spring foot 62 is in contact with the shoulder joining the forward end of the surface 63 with the 65 under edge of the slide as indicated in Fig. 2.

From the rear end of the horizontal portion of the surface 63, the under side of the slide 56 is formed to have a downwardly extending button 70 or cam 64 back of which is a recess 65 so that when the slide 56 is moved sufficiently to lift the rocker bar 17 to its uppermost position, the spring foot 62 will have been depressed by the cam 64 and then reposes within the recess 65 so 75 as to retain the slide 56 in that position. Thus

by rocking the inner handle 50, the handle may be turned to that position wherein the gear sector 54 has carried the slide 56 to lift the bar 17 out of influence from the handle 33 and the spring 30 will maintain that position of the 5 various members, it being noted that the hump 31 of the spring is still in contact with the inner end of the latch bolt 13 so as to maintain it at the same time in the latched position. Rocking of the inner handle 50 in the reverse direction 10 will cause the cam 64 to depress the spring foot 62 sufficiently to allow the cam 64 to pass there-over as the slide 56 returns to its normal position. It is further to be noted that the spring 30 pushing downwardly on the rocker bar 17 serves effectively through the contact of the bar 17 with the sloped face of the foot 61 to retain the slide 56 in that normal position bearing against the spring foot 62.

I find it desirable to provide a lug 66 on that 20 edge of the latch bolt 13 which is in sliding contact with the slide 56 and to provide the slide itself with a slot 67 into which this lug enters. Preferably this lug 66 is formed to have its fore 25 and aft edges or faces sloped from the upper end both inwardly toward the vertical axis of the lug and also to form the ends of the slot 67 with correspondingly sloped faces in a somewhat dove-tailed manner so that when the slide 56 reaches either end of its travel along the latch 30 bolt 13, there will be no tendency for either end of the slide 56 to lift away from the latch bolt 13.

The lug 66 serves for a further purpose in that when in contact with the forward end of the slot 67 as indicated in Fig. 2, the inner door handle 50 may be rocked clockwise in respect to Fig. 2 to cause the gear sector 54 to carry the slide 56 backwardly and thus push against the lug 66 and carry the latch bolt 13 backwardly to an unlatched position in opposition to the spring 30. 40 The length of the slot 67 is proportioned in respect to the lug 66 so that the slide 56 may travel toward the bar 17 from its normal position without interference by the lug but when traveling backwardly from the normal position will carry 45 the lug 66 therealong and thus shift the latch bolt 13. In this backward shifting of the latch bolt 13 into the retracted position, the rear end of the latch bolt 13 pushes against the hump 31 of the spring 30 to carry the spring around into 50 some such position as indicated by the dash lines, Fig. 2, where the end 62 is out of contact with the slide 56. However spring pressure is maintained through the train of elements back to the handle 50 by reason of the spring still bearing 55 against the latch bolt 13 and the lug 66 being in contact with the forward end of the slot 67. By reason of the peculiar formation of the spring 30, it is to be seen that a sufficient pressure may be maintained against the latch bolt 13 to insure 60 positive travel thereof while at the same time the end 62 may spring downwardly, bending within the hump 31 without undue pressure in a vertical direction against the slide 56.

Now should the door handle 50 inadvertently or 65 otherwise have been rocked to carry the slide 56 outwardly to have shifted the rocker bar 17 upwardly out of influence from the handle 33 when the door 11 is in an open position, the door may be safely slammed shut without in any way damaging the mechanism since the latch bolt 13 will 70 push inwardly against the spring 30 to tend to rock the end 62 below the cam 64 while at the same time the slide 56 is being carried rearwardly by reason of contact of the lug 66 with the 75

rear end of the slot 67. Thus as the door is shut, the slide 56 will be pushed back to its normal position thereby releasing the bar 17 and permitting it to drop under the influence of the spring 5 23. The door may then be locked from the outer side by the lock 45 or may be secured from the inside by rocking the handle 50 forwardly or toward the outer end of the latch bolt 13.

In some installations, the latch bolt 13, Fig. 6, 10 may have to be mounted to be in reversed position from that shown and described previously and at the same time maintain the handle in the same position. For such installations, the latch mechanism independently of the handle 33 above 15 described may be installed in reverse position. Now in place of the handle 33, a handle 68 is provided to be normally carried in the form as herein shown within the recess or countersink 69 and has a heel 70 slidably passing through an 20 opening in the metal 40 in such relation to the handle pivot pin 71 and so formed with the arcuate surfaces 72 and 73 that no opening is left at any time between the edges of the hole through the metal and heel 70 as it swings through that 25 opening. An arm 74 extends from around the pin 71 as an integral part and extension from the heel 70 to have a slotted end receive a pin 75 which is carried in one arm of a bell crank 76 which is rockably supported by the door. The other arm 30 of this crank 76 has pivotally secured thereto a link 77 which then extends back to have a finger 78 in the path of the leg 32 which extends laterally from the rocker bar 17. A suitable torsion spring 79 is wrapped about the pin 71 to return 35 the handle 68 to its normal position within the countersink 69. Some support is, of course, given to the link 77, here shown as by a bracket 80, to maintain the free end of it in proper relation to the leg 32.

40 Of course, when the device is to be employed on automobiles, it is not necessary to employ the outside lock on but one door, and in such event, the upper arm 21 and lip 22 on the bar 17 may be omitted on those doors not having the locking 45 cylinder 45.

While I have herein shown and described my invention in the one best form as now known to me, it is obvious that structural changes may be made therein without departing from the spirit 50 of the invention and I, therefore, do not desire to be limited to that precise form beyond the limitations as may be imposed by the following claims.

I claim:

1. In a door latching device, a latch bolt, a 55 spring urging the latch bolt into latching position, a latch bolt rocker mounted to be swingable into engagement with the latch bolt to retract the latch bolt against the pressure of said spring, an operating arm swingably mounted to travel 60 against said rocker to shift said latch bolt, said rocker being also shiftable to a position out of the path of said arm, spring means normally urging the rocker into the path of said arm, and a lock mechanism having a member engaging and shifting said rocker from said arm path upon placing said mechanism in a locked condition, the shifting of said rocker being transversely of said latch bolt, an arm extending laterally from the rocker to be contacted by said operating arm, and to be removed from said path by said rocker shifting.

2. In a door latching device, a latch bolt, a 75 spring urging the latch bolt into latching position, a latch bolt rocker mounted to be swingable into engagement with the latch bolt to re-

tract the latch against the pressure of said spring, an operating arm swingably mounted to travel against said rocker to shift said latch bolt, said rocker being also shiftable to a position out of the path of said arm, spring means normally urging the rocker into the path of said arm, and a lock mechanism having a member engaging and shifting said rocker from said arm path upon placing said mechanism in a locked condition, the shifting of said rocker being transversely of said latch bolt, an arm extending laterally from the rocker to be contacted by said operating arm, and to be removed from said path by said rocker shifting, an operating handle swingable toward and away from the door, to actuate said operating arm. 15

3. In a door latching device, a latch bolt, a spring urging the latch bolt into latching position, a latch bolt rocker mounted to be swingable into engagement with the latch bolt to retract the latch against the pressure of said spring, an operating arm swingably mounted to travel against said rocker to shift said latch bolt, said rocker being also shiftable to a position out of the path of said arm, spring means normally urging the rocker into the path of said arm, and a lock mechanism having a member engaging and shifting said rocker from said arm path upon placing said mechanism in a locked condition, the shifting of said rocker being transversely of said latch bolt, an arm extending laterally from the rocker to be contacted by said operating arm, and to be removed from said path by said rocker shifting, an operating handle swingable toward and away from the door, to actuate said operating arm, and spring means returning said handle to its normal inoperative position independently of said latch urging spring. 20

4. In a door latching device, a shiftable latch bolt, spring means urging the latch bolt to a latched position, a latch bolt rocker transversely shiftable across the latch bolt, spring means for shifting the rocker to one end of travel across the latch bolt, a stop on the latch bolt normally resting against said rocker, said rocker being swingable toward said latch bolt stop, stop means limiting reverse swinging of the rocker, an operating member swingable against said rocker to shift the latch bolt through said latch bolt stop against the latch bolt spring, and means for transversely shifting said rocker against the rocker spring 30 and out of the path of said arm, said means comprising a slide having a cam face, a shoulder on the rocker in the path of said face and a handle interconnected with the slide to carry said face against the shoulder to shift said rocker, a slide 35 engaging member carried by the latch bolt permitting said slide to be moved to cause said shifting but being engaged by the slide upon its travel away from said shoulder whereby the latch bolt is carried along with the slide. 45

5. In a door latching device, a shiftable latch bolt, spring means urging the latch bolt to a latched position, a latch bolt rocker transversely shiftable across the latch bolt, spring means for shifting the rocker to one end of travel across the latch bolt, a stop on the latch bolt normally resting against said rocker, said rocker being swingable toward said latch bolt stop, stop means limiting reverse swinging of the rocker, an operating member swingable against said rocker to shift the latch bolt through said latch bolt stop against the latch bolt spring, and means for transversely shifting said rocker against the rocker spring and out of the path of said arm, said means comprising a slide having a cam face, 50

a shoulder on the rocker in the path of said face and a handle interconnected with the slide to carry said face against the shoulder to shift said rocker, said slide interengaging said latch bolt with lost motion such that the latch bolt is not moved by the slide upon its travel to shift said rocker, but the latch bolt is retracted by reverse travel of the slide following the return of the rocker to its normal position, said handle 10 being moved in the reverse direction to retract the latch bolt.

6. In a door latching device, a shiftable latch bolt, spring means urging the latch bolt to a latched position, a latch bolt rocker transversely shiftable across the latch bolt, spring means for shifting the rocker to one end of travel across the latch bolt, a stop on the latch bolt normally resting against said rocker, said rocker being swingable toward said latch bolt stop, stop means 15 limiting reverse swinging of the rocker, an operating member swingable against said rocker to shift the latch bolt through said latch bolt stop against the latch bolt spring, and means for transversely shifting said rocker against the 20 rocker spring and out of the path of said arm, said means comprising a slide having a cam face, a shoulder on the rocker in the path of said face and a handle interconnected with the slide to carry said face against the shoulder to shift said 25 rocker, said slide interengaging said latch bolt with lost motion such that the latch bolt is not moved by the slide upon its travel to shift said rocker, but the latch bolt is retracted by reverse travel of the slide following the return of the 30 rocker to its normal position, said handle being moved in the reverse direction to retract the latch bolt, said interengaging means comprising a lug on one member entering a slot in the other, the ends of the slot and the lug faces being formed 35 to effect a dove-tail engagement at each end of the slot as the lug travels thereto whereby the slide and latch bolt may not rock away one from the other.

7. In a door latching device, a shiftable latch bolt, spring means urging the latch bolt to a latched position, a latch bolt rocker transversely shiftable across the latch bolt, spring means for shifting the rocker to one end of travel across the latch bolt, a stop on the latch bolt normally resting against said rocker, said rocker being swingable toward said latch bolt stop, stop means 40 limiting reverse swinging of the rocker, an operating member swingable against said rocker to shift the latch bolt through said latch bolt stop against the latch bolt spring, and means for transversely shifting said rocker against the 45 rocker spring and out of the path of said arm, said means comprising a slide having a cam face, a shoulder on the rocker in the path of said face and a handle interconnected with the slide to carry said face against the shoulder to shift said 50 rocker, said latch bolt spring also engaging said slide to initially maintain said face normally against said shoulder and thereafter yieldingly retain the slide in its shifted position of holding said rocker out of the path of its said operating member.

8. In a door latching mechanism, a slidable latch bolt, means constraining the movement of the latch bolt to longitudinal travel, a spring bearing against and urging the latch bolt in one direction of said travel, a swingably mounted 55

rocker bar extending in a direction transversely of the latch bolt and shiftable longitudinally, means preventing the swinging of the bar when longitudinally shifted, stop means interposed between said latch bolt and said bar limiting the travel of the latch bolt therewith under the influence of said spring, said bar being provided with means limiting its swing in one direction as induced by said spring through said stop means, a spring normally yieldingly maintaining said bar against longitudinal shifting, a door handle, an interconnecting arm between the handle and said bar, said bar having a member normally in the path of said arm but removed from said path upon longitudinal shifting of said bar.

9. In a door latching device, a latch bolt, a rocker mounted to be swingable along the bolt, an abutment on the bolt against which the rocker may press to shift the bolt, said rocker also being mounted to be shiftable transversely of the bolt, an abutment preventing swinging of the rocker when transversely shifted, means for transversely shifting the rocker, a door handle, swingable toward and away from the door, an arm extending from the door handle to have an end in the path of said rocker whereby said handle may swing said rocker when not in its transversely shifted position, said rocker having a face of appreciable area in the path of said end, and said end carrying a ball whereby said arm may contact and slide on said face through a range of handle mounting angles.

10. In a door latching device, a latch bolt, a rocker mounted to be swingable along the bolt, an abutment between the bolt and the rocker engageable upon swinging of the rocker, said rocker also being mounted to be shiftable transversely of the bolt, an abutment preventing swinging of the rocker when transversely shifted, means for shifting the rocker transversely of the bolt, a door handle, and an arm extending from the handle into the swinging path of the rocker.

11. In a door latching device, a latch bolt, a rocker mounted to be swingable along the bolt, an abutment between the bolt and the rocker engageable upon swinging of the rocker, said rocker also being mounted to be shiftable transversely of the bolt, an abutment preventing swinging of the rocker when transversely shifted, means for shifting the rocker transversely of the bolt, a door handle, and an arm extending from the handle into the swinging path of the rocker, said rocker being longitudinally shiftable along guide posts, one of the posts serving as the pivot about which the rocker may swing, and said rocker having an arcuate slot for passing the other of said posts to permit said swinging, the rocker carrying said slot past the said other post to effect said abutment when the rocker is shifted transversely of the bolt.

12. In a door latching device, a latch bolt, a rocker mounted to be swingable along the bolt, an abutment between the bolt and the rocker engageable upon swinging of the rocker, said rocker also being mounted to be shiftable transversely of the bolt, an abutment preventing swinging of the rocker when transversely shifted, a door handle actuated member in the path of said rocker formed to effect shifting of said rocker and means releasably retaining said member in engagement with said rocker.

ROBERT P. KUSZMAUL.
